UNITED STATES PATENT OFFICE.

HERMAN DAVIS, OF SHEBOYGAN, WISCONSIN.

TRUNK.

Application filed December 31, 1921. Serial No. 526,313.

To all whom it may concern:

Be it known that I, HERMAN DAVIS, a citizen of the United States, residing at Sheboygan, in the county of Sheboygan and 5 State of Wisconsin, have invented new and useful Improvements in Trunks, of which the following is a specification.

My present invention pertains to wardrobe trunks, and it contemplates the provision of a trunk of the type set forth, that is inexpensive to produce, simple in construction, and one through the medium of which the cover may be locked on the contents of the body portion of the trunk either 10 with the wardrobe tray encased by the body and cover portions or with the tray in its upright position outside the body of the trunk.

The invention further contemplates the 20 provision of a trunk of the character specified that is composed of no complicated elements or features that are liable to become inoperative after a short period of use.

The invention in all of its details, will be 25 fully understood from the following description and claims, when the same are read in connection with the drawings, accompanying and forming part of this specification, in which:

30 Figure 1 is a perspective view illustrating the trunk in its open position, but with the wardrobe tray within the trunk body.

Figure 2 is a longitudinal sectional view 35 of the trunk in its closed position.

Figure 3 is a perspective view illustrating the trunk as entirely open and showing the wardrobe tray in its upstanding position outside of the trunk body portion.

Figure 4 is a transverse central sectional 40 view showing the trunk in its closed position.

Referring by numerals to the said drawings in which like numerals indicate similar parts in all of the views, 1 indicates the body 45 portion of my novel trunk that is similar to the body portions of trunks now on the market with the exception that I remove a portion from the side wall of the trunk body preferably from the left hand side wall and 50 by removing or cutting away the left hand wall, I produce the edge indicated by the numeral 2.

Adapted to rest either upon the cleats 4 or 55 upon another tray placed in the body portion, is my novel wardrobe tray 3, that is constructed after the manner of trays in

use and extends the full length and width of the body portion, and to the left hand side wall of the tray 3, I secure in any approved manner the board or portion 5. This portion 5 is so secured to the tray wall that it will fully cover the space removed from the side wall of the trunk when said trunk is in its closed position, and the upper edge of the board portion 5 is adapted to receive 60 the lower edge of the top 9 of the trunk and be completely surrounded by the band or "valance" 10 of said top when said top has been closed down on the trunk body portion 1.

Secured to the underside of the tray 3, as clearly shown in Figures 2 and 4, by means of the straps 7 is a rod or roller 6, that is adapted to travel in the grooves or channels 8 formed in the inner front and rear walls 70 of the body portion 1 of the trunk.

It will be manifest from the foregoing that the tray 3 is formed the full length of the trunk, and may go down into the body portion 1 or up into the top 9 to any desired 80 distance in accordance with the depth of the tray, and that the left hand wall of the body portion is cut down level with the bottom of the tray, irrespective of the depth the tray extends into the trunk. Moreover, the portion 5 that is removed from the side wall is fastened to the left hand side of the wall of the tray so that said tray will 85 rest in a horizontal position on the cleats 4 or a lower tray as the case may be, 90 and when said tray is thus positioned, the portion removed from the body portion 1, will completely close the opening produced by the removal of the portion 5 from said left hand wall of the body portion 1. By 95 this arrangement, the trunk either with the top or lid 9 opened or closed will present a finished appearance and will resemble any trunk of similar features now in use. When the top or lid 9 is in its opened position, the 100 wardrobe tray 3, may be moved on the roller 6 to the left and carry the portion 5 with it until said tray arrived at a position, where the roller or rod will prevent further left hand movement of the tray. The tray may be 105 provided with a handle or lifter on its inner right hand wall, and when said tray has arrived at the limit of its left hand movement, the person practicing the invention may then grip the handle or lifter and tilt the 110 tray to the position illustrated in Figure 3. Manifestly the tray may be provided with

hinges whereby it is secured in a hinged manner to the left hand side wall of the body portion 1, in lieu of the rod or roller and channels illustrated, and I would also 5 have it understood that the tray may either rest upon the floor or other surface or the hinges may be so positioned that said tray will be retained clear of the floor when in its upright position.

10 It will be manifest that when the tray is in its upright position, the lid or cover 9 may be locked upon the body portion of the trunk to prevent access to the body of the trunk and the said upright portion or tray 15 3 left outside of the trunk.

I would distinctly have it understood that I do not wish to confine myself to the cutting away of the left hand wall of the body portion as in practice the right hand wall 20 may be cut away or removed in any manner compatible with the purpose of this invention.

It will be apparent that the roller or rod 6 will limit the outward movement of the 25 tray and the said tray may be positioned with respect to the roller that when it leaves its center of gravity it will automatically fall into its upright position. However, when the rod or roller 6 has arrived at the 30 point directly above the upper edge of the cut out portion further movement of the tray in a horizontal position is precluded.

The tray 3, moreover, may be employed after the manner of any tray other than a 35 wardrobe tray without departure from the scope of the appended claims.

When desired I may hinge one end of the tray and preferably the end indicated by 3^a, to the bottom of the tray by means of the 40 hinge 3^b and I make this provision in order that a person may look down into the tray and locate any garment desired without disturbing the remainder of the garments, and I also prefer to provide the top 9 with the 45 follower 9^a upon which the springs 9^b bear and force the follower 9^a into the tray in order to compress the contents of said tray and hold the garments therein secure, straight and in proper position irrespective 50 of the position at which the trunk is moved.

Having described my invention, what I claim and desire to secure by Letters-Patent, is:

1. In a wardrobe trunk, the combination 55 of a body portion having one side wall thereof cut away, a tray adapted to rest in the body portion, and having the portion of the side wall that has been cut therefrom secured to one of its side walls, a channel 60 formed in the body portion and a roller secured to the underside of the tray and adapted to travel in the channel for limiting the horizontal movement of the tray with respect to the body portion.

65 2. In a wardrobe trunk, the combination

of a body portion having a portion removed from one of its walls, a tray arranged in the body portion and having the portion that is removed from the body portion secured to one of its side walls, and a roller secured to 70 the underside of the tray at a point slightly beyond the center thereof for limiting the movement of the tray in a horizontal manner with respect to the body portion and further being adapted to act as a pivot for 75 the tray whereby said tray may be swung to a vertical position with respect to the body portion.

3. In a wardrobe trunk, the combination 80 of a body portion having one of its side walls partially cut away by removing a portion of said wall, a tray pivotally mounted in the body portion by means of a roller secured to the under side of the tray, a set of 85 channels formed interiorly of the front and back walls of the body portions and extending from the transverse center of the trunk to the cut-away side wall; said cut-away portion of the side wall being secured to one end of the tray whereby it acts as a support 90 when the tray is standing in a horizontal position and further acts as a closure for the cut-away side wall when the tray is thrown into its normal position within the body portion. 95

4. In a wardrobe trunk the combination 100 of a body portion having one cut away side wall, a tray having one end thereof hinged to its bottom portion; said tray adapted to rest in the body portion and having the portion of the side wall that has been cut from the body portion secured to the unhinged wall of the tray, a channel formed in the body portion, a roller secured to the under side of the tray and adapted to travel in the 105 channel, a top hinged to the body portion, and a spring-backed follower board secured within the top and adapted to enter the upper end of the tray.

5. In a wardrobe trunk, the combination 110 of a body portion having one of its side walls partially cut away by removing a portion thereof and a tray having means secured to its underside whereby it is pivotally mounted with respect to the body portion; said 115 cutaway portion of the side wall being secured to one end of the tray whereby it acts as a support when the tray is standing in a horizontal position outside of the body portion and further acts as a closure for the cutaway side wall when the tray assumes its normal position within the body portion. 120

In testimony whereof I have hereunto set my hand in presence of two subscribing witnesses.

HERMAN DAVIS.
